UNITED STATES PATENT OFFICE

HERMAN F. BRANSTETTER AND BERTHA W. BRANSTETTER, OF FORT PIERCE, FLORIDA

SUN-BATH TENT

Application filed September 26, 1928. Serial No. 308,410.

The present invention relates to an improved tent structure designed especially for permitting persons to take an out-of-doors sun bath.

- 5 Our principal aim is to provide a suitable tent for the occupant which will conceal the occupant from view, and thereby provide the desired privacy, this tent being characterized by an especially designed side wall made to 10 form an open top inclined sun chute, whereby to permit the occupant to remain within the confines of the tent proper while yet subjecting the body to the sun rays entering the open side by way of the chute.
- 15 In carrying out the invention, we have produced a structure which is distinguished by the aforesaid features, and also by the additional features of compactness and convenience of arrangement of parts, in order 20 to permit the tent to be easily erected or folded up for transportation, to permit the chute to be extended for use when desired, or permit it to be folded to provide a closed wall for the normally open side when desired.
- 25 Other features and advantages of the invention will become more readily apparent from the following description and drawings.

In the drawings:

Figure 1 is a top plan view of a sun bath 30 tent constructed in accordance with the present invention, showing it set up for use.

Fig. 2 is a front end elevational view of same.

Fig. 3 is a cross sectional view through the 35 structure.

Fig. 4 is an inverted perspective view of a removable top.

Fig. 5 is a perspective view of the rear end wall.

40 Fig. 6 is a fragmentary sectional and elevational view showing the manner in which the top reach rod is associated with the end support.

Fig. 7 is a view showing the manner in 45 which the canvas is buttoned to the poles.

Fig. 8 is a perspective view of one of the poles.

Fig. 9 is a perspective view of the sectional 50 reach rod, and

Fig. 10 is a fragmentary perspective view

on an enlarged scale, showing the manner in which the sections of the end supports are joined together for reception of the end portions of the reach rod.

The tent proper comprises a single piece 55 back or rear end walls 11, a normally closed side wall 12, (see Fig. 3), and a front end wall composed of separably connected sections 13 and 14. These walls are buttoned or otherwise separately fastened as at 15 to 60 the corner poles 16. Each pole is of the construction shown in Fig. 8. That is, it is made of sections 17 and 18 hingedly connected together at 19, and fastened in operative relation by a hook 20 extending through a complementary eye 21.

The pole is formed at its top with the usual 65 pintle pin 22. There are two of these pin equipped poles employed for supporting the side sun chute, 23. The other poles, although 70 being made up of hinged sections and constructed in the same way, as the one already described, are distinguished by the reference characters 24. This is done because these 75 poles are used in forming a sort of a frame work. Each frame work comprises a pair of sectional poles and the cross piece support for the top. This comprises a pair of duplicate sections 25, pivotally connected at 26 to the poles, and joined together as shown 80 in Fig. 10.

A pair of channel-shaped brackets 27 are 85 employed for the same purposes, these brackets being pivotally connected together at 28 and so constructed at their adjacent ends as to provide a notch 29 forming a keeper seat for reception of the adjacent end of the reach rod 30, seen in Fig. 9. The reach rod is composed of hingedly connected sections 31 having notched clips 32, at their ends which are placed in the seat 29 in an obvious manner. In this way the two end frames can be set up and the reach rod placed in position to temporarily hold them there, after which the stay wires or ropes 33, which are provided, 90 may be staked to the ground.

With the frame structures thus set up, the 95 canvas end walls and side walls can be easily buttoned in place. Then, there is a top or cover 34 provided. This is somewhat in the 100

form of a cap, the same being constructed of canvas and of a shape shown in Fig. 4, and having side and end flanges 35 which fit telescopedically around over the frame work and side walls as shown.

5 As is obvious, the right hand side of the tent in Fig. 3 is opened to allow the sun rays to pass through into the interior of the tent to impinge on the body of the occupant. This 10 is the reason for providing the chute 28. The chute comprises an inclined bottom wall 36 and substantially triangular end walls 37 detachably fastened to the end frame structures.

15 With this arrangement, it is obvious that the occupant of the tent, though concealed from exterior view, may have full advantage of the sun rays entering the open side of the tent by way of the inclined chute which is 20 associated with the side. In practice it is found advisable to provide the bottom wall 36 of the chute with additional fasteners 38 so that it can be folded up and fastened in a vertical position for closing the previously 25 opened side.

From the foregoing description and drawings it will be seen that we have evolved and produced a novel knock-down tent structure which is characterized by unusual compactness and convenient arrangement of parts. 30 It is practicable from a standpoint of transportation and erection.

Moreover, it is dependable and advantageous in insuring the obtainance of a proper 35 and desirable sun bath, while maintaining desired privacy and successful exposure of the body to the sun rays. It is thought however, that the simplicity of the invention is such as to permit a clear understanding of the construction, operation and advantages 40 to be had. Therefore, a more lengthy description is regarded unnecessary.

Minor changes in shape, size, and arrangement of materials, coming within the field 45 of invention claimed, may be resorted to in the usual practice if desired.

Having thus described our invention, what we claim as new is:—

1. In a structure of the class described, 50 an enclosure open on one side to permit passage of sun rays into the interior of the enclosure, and a sun chute cooperable with said open side, said sun chute having an inclined bottom and end walls, and being open 55 at its top.

2. In a structure of the class described, a tent open on one side, and a sun chute for said open side, said sun chute being open at its top and including an inclined bottom, and 60 vertical end walls.

3. In a structure of the class described, a tent open on one side, and a sun chute for said open side, said sun chute being open at its top and including an inclined bottom, 65 and vertical end walls, said sun chute being

composed of foldable fabric separably connected with the tent proper and convertible by folding from the chute to a vertical side wall for closing the previously opened side walls of the tent.

4. In a structure of the class described, a tent comprising a pair of end frames, each frame including sectional poles and cross supports, each support embodying sections, and coupling members at the inner ends of 70 said sections, for hingedly connecting said sections together, said coupling members being constructed to provide keeper seats therebetween, a sectional reach rod having notched clips at its opposite ends for removable reception in the keeper seats, fabric tent forming walls for cooperation with said frame, one of said walls constituting a top 75 and being in the form of a cap having marginal portions, another one of said walls being designed to form a sun chute together with supplemental poles for supporting said chute in operative position whereby to provide an inclined bottom wall, vertical end walls, and an open top for passage of sun 80 rays.

In testimony whereof we affix our signatures.

HERMAN F. BRANSTETTER.
